T. M. DAVIDSON AND J. CHESNEY.

TAMPING MACHINE.

APPLICATION FILED JUNE 13, 1918

1,372,009.

Patented Mar. 22, 1921.

UNITED STATES PATENT OFFICE.

THOMAS MALCOLM DAVIDSON, OF WILMINGTON, DELAWARE, AND JOHN CHESNEY, OF GIBBSTOWN, NEW JERSEY, ASSIGNORS TO E. I. DU PONT DE NEMOURS & COMPANY, OF WILMINGTON, DELAWARE, A CORPORATION OF DELAWARE.

TAMPING-MACHINE.

1,372,009.

Specification of Letters Patent. Patented Mar. 22, 1921.

Application filed June 13, 1918. Serial No. 239,743.

To all whom it may concern:

Be it known that we, THOMAS M. DAVIDSON, of Wilmington, in the county of New Castle and State of Delaware, and JOHN CHESNEY, of Gibbstown, in the county of Gloucester and in the State of New Jersey, have invented a certain new and useful Improvement in Tamping-Machines, and do hereby declare that the following is a full, clear, and exact description thereof.

Our invention relates particularly to a machine adapted to be used in the tamping of explosives or other materials to be filled into shells.

15 The object of our invention is to provide a machine of this character which will fill shells and bombs of many different sizes with explosives or other materials that are dry or moist, to a predetermined density, 20 even when most difficult mixtures of materials are used.

A further object is to provide an apparatus of this character which will fill the shells with great safety to the operator and 25 which can be used to fill a considerable number of shells simultaneously.

Another object is to provide a machine of this kind which will fill the shells while in an upright position, so that the shells may 30 be fed beneath the machine, thus eliminating the manipulation of the shells prior to loading, so far as possible.

Still another object of our invention is to provide a machine by the use of which materials deleterious to the health of the operator, as for example materials used in smoke and gas shells, etc., may be loaded into the shells without affecting the operator.

Again, an object of our invention is to 40 provide a machine by which the explosives or other materials may be introduced into shells in distinct strata.

Further objects of our invention will appear from the detailed description thereof 45 contained hereinafter.

While our invention is capable of embodiment in many different forms, for the purpose of illustration we have shown only one

form of our invention in the accompanying drawings, in which—

Figure 1 is a vertical section of an apparatus made in accordance with our invention; and

Fig. 2 is a vertical section of a detail enlarged.

In the drawings, we have shown a framework 1, adapted to be connected to a floor 2, said framework comprising a plurality of uprights 3, 4 and 5, connected by crossbeams 6, 7 and 8. Upon the floor 2 there are provided tracks 9 for receiving a truck 10, adapted to carry a plurality of shells 11, having central openings 12, to receive the explosive or other materials to be tamped into the same. Each shell 11 rests upon a cup-shaped support 13, having a downwardly-directed projection 14, provided with a tapered recess 15 to receive a center point 16 carried by a piston 17, which reciprocates in a cylinder 18, supplied with compressed air by a pipe 19. The cup-shaped support 13 is rotated in an inclined position by frictional contact with a friction wheel 20 located on a shaft 21 and pressed against a support 13 by a spring 22 located between one of a pair of bearings 23 and 24 for the shaft 21 and a driving pulley 25. The driving pulley 25 is rotated by a belt 26, passing over a pulley 27, on a shaft 28, supported in a bearing 28^a from the upright 3, which shaft carries a larger pulley 29, driven by a belt 30 from a pulley 31 on a main driving shaft 32, supported on the upright 3 by a bearing 33. The shaft 32 is driven by means of a pulley 34 carried thereon and a belt 35 connected with any suitable source of power.

Supported upon crossbeam 8 there is an air cylinder 36 adapted to be supplied with compressed air by a pipe 37 to move a piston 38, to which is attached a tamping rod 39, having a stop 40 to coöperate with a frictional driving member 41, which is comprised of a central split sleeve 42, having a housing 43, carrying a plurality of thumb-screws 44 to adjust the pressure upon the rod 39. The frictional driving member 41

has a pivotal connection to a link 45, which is connected to a crank 46 on the shaft 32. By this means the rod 39 is reciprocated. Around the rod 39 there is located a rotary sleeve 47, carrying a pulley 48, driven by a belt 49, passing over an idler 50 and over a driving pulley 51 on shaft 32. On the outside of the sleeve 47 there is a larger sleeve 53, carrying a bevel gear 54, which is driven 10 by a bevel gear 55 on the shaft 28. The sleeve 53 carries a spiral stirrer 56, which is located in a hopper 57, while the sleeve 47 carries a helical blade 58 located in the mouth of said hopper 57, which is designed 15 to project into the shell 11. Within the shell 11, the tamping rod 39 carries a head 59, having a tapered end 60, the side of which is substantially parallel to the nearest portion of the inclined inner surface of the shell 11. Said head 59 may be made of wood, brass, 20 steel or hard rubber, or any other suitable material.

In the operation of our invention, the shells 11 will be fed forwardly from time 25 to time to the tamping machine by moving the trucks 10 on the rails 9. It will be understood that, of course, any number of these tamping machines may be operating simultaneously on the trucks carried by the 30 same set of tracks 9. When a particular shell 11 has reached a position beneath the tamping rod 39, which has been previously withdrawn by operating the air cylinder 36, so that the cup-shaped support 13 rests upon 35 the pin or plunger 15 and the edge of said support 13 is in contact with the friction wheel 20, the air cylinder 36 is operated to move the rod 39 downwardly to the lowest position available in the shell 11. Power is 40 thereafter applied to the tamping machine by the belt 35, and the materials, as for example explosives in the form of dry grains, are fed into the hopper 57. The tamping rod 39 will be continually reciprocated by the 45 friction driving member 41, while the said shell 11 will be continually rotated by the friction wheel 20 in an inclined position. The stirrer 56 will keep the materials in a continual state of agitation in the hopper 50 57, so that they will be easily and uniformly fed from the same while the blade 58 will feed the materials from the hopper 57 into the shell 11. As the materials in the shell 55 gradually accumulate and are packed in place, the tamping rod 39 will slip upwardly in the friction driving member 41 from time to time on the downward stroke, so that a predetermined density may be obtained, which density will be determined by the position of the thumbscrews 44.

When at any time during the tamping operations, or at the end of the tamping operation, it is desired to withdraw the tamping rod 39, this may be done by the operation 60 of the air cylinder 36, the stop 40 op-

erating to limit the upward movement of said tamping rod.

When the tamping operation has been completed and the tamping rod 39 has been withdrawn, the air cylinder 18 will be operated to lower the cup-shaped support 13 onto the truck 10, after which the truck may be moved forwardly to convey away the filled shell and permit other shells to be drawn into place in succession beneath the 75 tamping machine, to be filled in the same manner as above described.

It will be understood that, if different materials are to be packed into a particular shell in the form of strata, this may be readily done by feeding one material at one time and thereafter feeding another material.

While we have described our invention above in detail, we wish it to be understood 85 that many changes may be made therein without departing from the spirit of the same.

By the term shell appearing in the claims we mean to refer to any container for explosives, as for example, bombs, hand grenades, etc.

We claim:

1. A tamping machine comprising tamping devices, means to elevate a shell to the 95 same for filling in a substantially vertical position, and means for rotating the shell during the tamping operation.

2. A tamping machine comprising tamping devices, means to elevate a shell to the 100 same for filling in a substantially vertical position, and means for rotating the shell in a slightly inclined position during the tamping operation.

3. A tamping machine comprising tamping devices, means to elevate a shell to the 105 same for filling in a substantially vertical position, and means for rotating the shell in a slightly inclined position during the tamping operation, comprising a rotatable support, a vertically movable pivot for the same and a peripheral drive for the support.

4. A tamping machine comprising shell-holding means, a hopper for feeding the materials to be tamped, a screw feed in the 115 mouth of said hopper and a stirrer in said hopper, and tamping means comprising a tamping rod passing through a sleeve which carries the screw feed around which a sleeve 120 is provided carrying the stirrer.

5. A tamping machine comprising shell-holding means, a hopper for feeding the materials to be tamped and a screw feed in the mouth of said hopper tamping means, and a 125 friction driving device for reciprocating the tamping means.

6. A tamping machine comprising shell-holding means, a hopper for feeding the materials to be tamped, a screw feed in the mouth of said hopper and a stirrer in said 130

hopper tamping means, and a friction driving device for reciprocating the tamping means.

7. A tamping machine comprising shell-holding means, a hopper for feeding the materials to be tamped and a stirrer in the body of the hopper tamping means, and a friction driving device for reciprocating the tamping means, said tamping means being 10 coaxial with said stirrer.

8. A tamping machine comprising shell-holding means, a hopper for feeding the materials to be tamped, a screw feed in the mouth of said hopper and a stirrer in said 15 hopper, tamping means comprising a tamping rod passing through a sleeve which carries the screw feed around which a sleeve is provided carrying the stirrer, and a friction driving device for reciprocating the 20 tamping means.

9. A tamping machine comprising shell-holding means, a hopper for feeding the materials to be tamped and a screw feed in the mouth of said hopper tamping means, 25 a friction driving device for reciprocating the tamping means, and an air cylinder for operating the tamping means independently of the friction drive.

10. A tamping machine comprising shell-holding means, a hopper for feeding the materials to be tamped, a screw feed in the mouth of said hopper and a stirrer in said 30 hopper tamping means, a friction driving device for reciprocating the tamping means, 35 and an air cylinder for operating the tamping means independently of the friction drive.

11. A tamping machine comprising shell-holding means, a hopper for feeding the materials to be tamped and a stirrer in the 40 body of the hopper tamping means, a friction driving device for reciprocating the tamping means, and an air cylinder for operating the tamping means independently 45 of the friction drive.

12. A tamping machine comprising shell-holding means, a hopper for feeding the materials to be tamped, a screw feed in the mouth of said hopper and a stirrer in said hopper, tamping means comprising a tamping rod passing through a sleeve which carries the screw feed around which a sleeve is provided carrying the stirrer, a friction driving device for reciprocating the tamping means, and an air cylinder for operating the tamping means independently of the friction drive. 50

13. A machine of the class described, comprising a shell holder, a center point substantially in line with the longitudinal axis of the shell and adapted to engage said shell holder, means for rotating said holder when the latter is in position on said center point, and means for feeding material into 55 said shell during rotation thereof. 60

14. A machine of the class described, comprising a shell holder, a center point substantially in line with the longitudinal axis of the shell and adapted to engage said shell holder, means for rotating said holder when the latter is in position on said center point, means for feeding material into said shell during rotation thereof, and a reciprocable tamping device adapted to work 70 within the shell. 75

15. A machine of the class described, comprising a shell holder, means for moving the shell into position to be filled, a friction driving device engaged when the shell is moved into position to be filled to rotate the shell, and means for feeding material into 80 said shell during rotation thereof.

In testimony that we claim the foregoing we have hereunto set our hands.

THOMAS MALCOLM DAVIDSON.
JOHN CHESNEY.
